UNITED STATES PATENT OFFICE

CHESTER D. AINSWORTH, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH AND ARC EXTINGUISHING MEANS

Application filed August 19, 1930. Serial No. 476,258.

This invention relates to electric switches and arc extinguishing devices therefor.

The circuit interrupting arc that is drawn between the separating contact members of an electric switch, when the switch opens under heavy load, is difficult to extinguish, and persists usually until the arc has been attenuated to a relatively long extent. The length of duration of the heavy arc is sufficient to cause the contact members to become burned and large amounts of the oil or other liquid in which the arc is usually drawn to become vaporized, thereby building up a considerable and oftentimes dangerous gas pressure within the switch casing.

One of the objects of the present invention is the provision of improved means which is in intimate contact with the arc at the time the switch opens under normal load and which is a part of the circuit interrupting elements of the interrupter and which acts to cool and rapidly to extinguish the arc, and thereby avoid severe burning of the contact members and vaporization of the oil.

Another object of the invention is to force the arc out into a thin band or ribbon which is held against a cool insulating surface that abstracts heat from the ribbon and thereby rapidly de-ionizes and extinguishes the arc.

Another object of the invention is the provision of a relatively massive block of insulating material having a face which confronts and is close to the separable arcing members, and magnetic means to blow the arc that is formed between the arcing members against the face of the block, whereby the arc is cooled and extinguished.

A further object is generally to improve the construction and operation of electric switches.

Fig. 1 is a sectional elevation of such elements of an electric switch as are necessary to illustrate the invention.

Fig. 2 is a section taken along line 2—2 of Fig. 1.

Fig. 3 is a detail showing the relation between the arc and the cooling and arc extinguishing block.

Fig. 4 is a perspective view of a modified form of an arc-cooling block.

Fig. 5 is a detail illustrating the arc-cooling block carried by a wall of the switch casing.

Fig. 6 is a perspective view of the contact member supporting bracket which supports the arc cooling-block of Fig. 1.

Fig. 7 is a front view of the arc cooling-block having a further modified form of arc-engaging face.

The electric switch here shown as embodying the invention comprises stationary switch members 10, and a movable switch member 12. The stationary switch member includes an insulating bushing 14 having a conducting stud 16. An inverted brush member, or main current carrying member, 18 is located on the lower end of the stud and is secured thereto by upper and lower clamping nuts 20, 22, respectively, which are screw threaded on said stud on opposite sides of the brush member. A stationary auxiliary contact or arcing member 24 is located beneath the brush member. Said arcing member consists of a horizontally-disposed massive cylinder of copper or other suitable material, that is located between the depending ears 26 of a supporting frame and is secured to said frame by a bolt 28. Said frame has an upper horizontal member 30 which is disposed between the brush member 18 and the nut 20 and is secured to the stud 16 by said nut.

The movable switch member includes the lifting rod 32. A bridging member 34 of inverted channel shape is supported loosely on a stud 36 that is carried by the lower end of said lifting rod and serves to bridge and thereby electrically to connect the brush members 18 when the switch is closed. A supporting frame 38 of inverted channel shape is located between the depending flanges of the bridging member 34 and is rigidly secured to the stud 36 of the lifting rod. A conducting bar 40 is located between the depending flanges of said supporting frame and has a horizontal upper section which is carried by said frame, a downwardly reflexed or vertical outer section 42, a horizontal lower bottom section 44, and an upwardly reflexed or vertical inner end section 46, said member being similarly formed

at both ends although but one end being here shown. A rigid arm 48 is located between the aforesaid sections and is pivotally connected at 50 to the upper end of the inner vertical section 46. Said arm extends loosely through a slot 52 in the outer vertical section 42 and has a bifurcated outer end between which an auxiliary movable contact or arcing member 54 is secured. Said arcing member 10 is similar to the stationary arcing member 24 and engages said arcing member when the switch is closed. An insulating bushing 56 surrounds the arm 48 where it passes through the slot 52 whereby to prevent electrical contact between said arm and the section 42. A spring 58 bears against said bushing and a cup 60 is seated in an aperture of the horizontal section 44 whereby to urge said arm and the arcing member carried thereby toward the stationary arcing member. 15

When the switch is closed, the current passes from one auxiliary arcing member through the reflexed portions of the conductor bar 40 to the other arcing member. The magnetic reactions of the upper and lower portions of the conductor 40 with the contact carrying bar are such as to urge said bar upwardly toward the stationary arcing member 24 and thereby to maintain the movable arcing member in firm engagement with the stationary arcing member. The reflexed portions of the conductor 40 are located as close to the arcing members as is practicable so as to set up a strong magnetic field in the 20 arc zone between the arcing members and at right angles to the line of separation of said arcing members.

The reflexed portions thus exert a strong magnetic blow-out effect on the arc and force 25 it outwardly or toward the insulating lining 62 located adjacent the side wall 64 of the enclosing casing.

In accordance with this invention, I provide a massive block 66 of insulating material 45 which is vertically disposed close to the separable arcing members and between them and the casing wall. The block is suitably supported in the aforesaid position as by being secured to an extension 68 of the horizontal 50 section 30 of the contact supporting bracket

26. The block preferably is removably secured to said extension by the bolt 70 and nut 71. The block is provided with a vertical face 72 which closely confronts the arcing members 55 and said face is of substantial extent both in vertical and horizontal directions so that preferably it is of greater extent than the highly heated and conducting gas zone of the arc.

The magnetic reactions of the reflexed portions, or loop, of the conductor 40 is such 60 as to blow the arc into intimate contact with the face 72 of the block and to spread the arc gases as a thin band 74, Fig. 3, which lies in intimate contact with the surface of the block. The block is normally cold and thus

cools the arc and thereby quickly renders the gases thereof non-conducting. The magnetic action of the looped conductor 40 on the arc is particularly helpful since it spreads the gases out into a thin band so that the cool block can act throughout the entire thickness of the band; and it forces the gases into intimate contact with the block. Preferably the block is of some good heat-conducting and electrically-insulating material, such as a 70 carborundum block which not only has good heat conductivity for an electric insulator but also is highly resistant to the action of the arc. Other suitable materials, however, 75 may be employed. 80

This invention is particularly adapted to a switch wherein the separable arcing members are immersed in oil and the arc is drawn beneath the surface of the oil. With this 85 type of switch, the insulating block 66 preferably also is porous so that it can become impregnated with oil. The oil will be released at the surface 72 of the block when the arc is in engagement therewith and the cool oil will come into intimate contact with and cool the arc. The corborundum block aforesaid can be obtained in porous form with the pores indistinguishable to the eye. Other insulating blocks of good porosity also 90 can be obtained readily. The insulating block 95 not only acts by itself to cool and thereby extinguish the arc, but it holds the oil surrounding the arcing members in place during circuit interruption and thereby effects an additional deionizing and extinguishing 100 action on the arc. 105

While in Fig. 1 the arc receiving surface 72 is plane, in Fig. 4 it is provided with transverse corrugations 76 so as to increase 110 the length of surface that supports the arc and thereby the cooling effect on the arc. The corrugations 76 also retain oil which increases the effectiveness of the arrangement. In Fig. 7 the surface of the block is 115 grooved to provide a series of alternate arc-engaging projections 76a and indentations 77, the projections being of pyramidal configuration that act upon the arc to divide it into small streams and to cool and deionize the small streams.

It is not essential that the block 66 be supported by the stationary switch member. In Fig. 5 the block is supported by the insulating lining 62, said lining having Z-shaped brackets 78 that are located in transverse grooves 80 formed in the upper and lower faces of the block so that the block is removably retained in position. 120

I claim:

1. A circuit interrupter comprising separable contacts, an arc-extinguishing block of insulating material of high heat absorbing properties located parallel to the line of separation of said contacts and having a broad 125 face which confronts said contacts, and 120

means to blow the arc formed between the separated contacts forcibly against the flat face of the block, said block being so close to said contacts that, in combination with the blowout means, the arcs that are formed during the opening of the interrupter under its normal load are forced intimately against said block for the major portions of their lengths and give up their heat thereto and are thereby extinguished.

2. A circuit interrupter as defined in claim 1 wherein a casing encloses said contacts and block and wherein the block is supported directly by one of said contacts and is spaced away from the side wall of said casing.

3. A circuit interrupter comprising separable contacts, an insulating block of heat absorbing material located parallel to the line of separation of said contacts and having a broad face which confronts said contacts, means to blow the arc formed between the separated contacts against the flat face of the block, said block being so close to said contacts that, in combination with the blowout means, the arc that is formed during the opening of the interrupter under its normal load is forced against said block and gives up its heat thereto and is thereby extinguished, the arc engaging face of said insulating block being porous, and an arc extinguishing liquid contained in the pores which is liberated into the arc when the arc impinges thereagainst.

In testimony whereof, I have signed my name to this specification.

CHESTER D. AINSWORTH.
